LATCH MECHANISM

Archer L. Knapp, Detroit, Mich., assignor to
 Packard Motor Car Company, Detroit, Mich.,
 a corporation of Michigan

Application March 17, 1934, Serial No. 716,133

7 Claims. (Cl. 292—33)

This invention relates to latch mechanism for motor vehicle doors and has for its principal object the provision of mechanism for connecting the locks of two doors whereby simultaneous actuation of both locks may be effected by manipulation of a single operating means. In the preferred form of the invention, the locking mechanisms for adjacent front and rear doors at one side of a vehicle are interconnected to permit displacement to locking position of both locking mechanisms by operation of the usual manual control element associated with the front door. Thus with this construction it is possible to complete the locking of the vehicle body by means readily accessible from the front seat of the vehicle and the manipulation of the locking means associated with the rear door is rendered unnecessary.

It is a further object of the invention to provide means readily accessible from the front seat of the vehicle and preferably located adjacent the front door opening to permit the release of the locking mechanism for the rear door, as distinguished from the conventional arrangement which requires the operator to lean over the back of the front seat and reach into the rear portion of the vehicle body to admit passengers to the rear compartment.

Further objects and features of the invention will be apparent from the following description taken in connection with the accompanying drawings, in which

Figure 1 is a side elevational view of a vehicle body panel as viewed from the interior of the vehicle illustrating one mode of applying the invention thereto;

Figure 2 is an enlarged vertical sectional view through a portion of the structure shown in Figure 1 taken substantially on the line 2—2 of Figure 3;

Figure 3 is a horizontal sectional view on the line 3—3 of Figure 2;

Figure 4 is a fragmentary sectional view taken on the line 4—4 of Figure 3;

Figures 5 and 6 are sectional views corresponding to Figure 3 and illustrating modifications of the structure shown in the latter figure;

Figure 7 is a vertical sectional view corresponding to Figure 2 and illustrating a further modification;

Figure 8 is a fragmentary vertical sectional view taken substantially on the line 8—8 of Figure 7; and

Figure 9 is a sectional view taken on the line 9—9 of Figure 8.

In describing the invention reference will be made to the several modified forms thereof illustrated in the accompanying drawings and specific language will be employed. It will be understood, however, that by the use of detailed descriptive language no limitation of the invention is intended but that various further modifications are contemplated such as fall within the actual scope of the invention as defined in the claims appended hereto.

Referring first to the form of the invention shown in Figures 1 to 3 inclusive of the drawings, it will be observed that the body structure includes a front door 10, a rear door 11, and a pillar 12 intermediate the two doors, the doors being preferably hinged in the conventional manner at the sides thereof remote from the pillar 12 and engaging the latter only in the closed position. As illustrated in the drawings, the latch and locking mechanism for the two doors is similar, and the same reference numerals will therefore be employed to designate the corresponding parts.

Thus each door is provided with manually operable means accessible from the interior of the vehicle for controlling the latch and locking mechanism of the associated door, this means including a handle 15 carried by a shaft 16 which is journaled for rotation in the door panel in the usual manner. Each shaft 16 is provided with an arm 17 disposed within the door panel and connected by means of a link 20 with a locking plate 21, the latter being supported for reciprocal sliding movement on a latch plate or casing indicated generally at 22.

Carried by each latch casing 22 is a reciprocable latch bolt 25 having the usual bevelled striking portion 26 cooperating with a suitable keeper (not shown) in the pillar 12 in the conventional manner, a coil spring 28 carried by the latch casing 22 engaging a tongue 29 struck out from each latch bolt 25 to urge the latter toward the position shown in Figure 2 of the drawings in which the latch bolts cooperate with the respective keepers.

Each locking plate 21 is guided for sliding movement on and with respect to the associated latch bolt 25, for instance by means of cooperating flanges 31 and 32 formed on the locking plates and on the latches respectively, the latch bolts being supported in turn for sliding movement on the latch casing 22 in any suitable manner. A locking abutment or dog 35 is formed on or carried by each locking plate 21, the abutment 35 being supported against downward dis-

placement by means of a guide 36 carried by the latch casing 22. A lost motion connection is also provided between each locking plate 21 and the associated latch bolt 25, this connection including for instance a pin 38 carried by the latch bolt and extending through a slot 40 formed in the associated locking plate. As shown more particularly in Figure 2 of the drawings, this pin and slot connection affords considerable clearance between the latch and locking plate permitting limited relative movement of the two members. Thus on displacement of either locking plate 21 in a direction away from the pillar 12, the pin 38 will be engaged by one end of the slot 40 so that the latch bolt 25 is retracted from the keeper in the pillar 12, this movement of the locking plate being effected by rotation of the associated handle 15 in a clockwise direction and through the medium of the link 20, so that the door is permitted to swing open, the spring 28 returning the latch bolt to its normal position when the handle is released. If either handle 15 is rotated in a counterclockwise direction, the associated link 20 and locking plate 21 will be displaced toward the pillar, but the clearance between the pin 38 and that end of the slot 40 adjacent the link 20 is sufficient to permit the locking plate to be displaced without movement of the latch bolt 25. Such movement of the locking plate 21 serves to position the dogging abutment 35 carried thereby beneath the projection 43 formed on the roll back 42, the latter being in turn carried on the non-circular portion of the shaft 44 which is journaled in the door panel and which extends through the latter to the exterior of the vehicle and is provided with the usual handle 45. An arm 46 on the roll back 42 is arranged to engage a lug 47 struck out from the latch bolt 25.

When either handle 45 is operated from the exterior of the vehicle while the parts occupy the position in which they are shown in Figure 2, the roll back 42 and arm 46 will be rotated in a clockwise direction to withdraw the latch bolt 25 from the associated keeper in the pillar 12 and thereby permit opening of the door. If, however, the dogging abutment 35 has been positioned beneath the projection 43 on the roll back 42, such movement of the roll back 42 is prevented and the door cannot be opened from outside the vehicle.

The construction thus far described is more or less conventional and forms no essential part of the present invention except insofar as it operates with the mechanism hereinafter described. Thus the invention is equally applicable to other types of latch and locking mechanism ordinarily employed in connection with vehicle doors.

It will be observed that the latch casing 22 associated with the forward door of the vehicle is provided with guides 49 which may be substantially U-shaped in cross-section and which serve to support a member 50 also U-shaped in section, the latter being recessed as indicated at 51 to receive a cam 54, the rearward end of the recess 51 terminating in a lug 55 struck up from the member 50. The cam 54 is pivoted at 57 to the latch casing 22 and is provided adjacent its lower end with a roller 56 arranged for engagement by an abutment 59 secured to the locking plate 21, for instance by attachment to the upper flange 31 on the locking plate. As the locking plate 21 is moved rearwardly, the cam 54 will be rocked in a counterclockwise direction so that

the rearward face thereof which engages the lug 55 serves to displace the member 50 toward the pillar 12, return movement of the locking plate 21 producing no corresponding movement of the cam 54.

A link 60 is pivoted at one end to the member 50 by means of a pin 62 and its opposite end by means of a pin 63 to a member 64, the latter being in turn fulcrumed for pivotal movement as at 65 on the latch casing 22 and being disposed adjacent an opening 67 in the edge panel 68 of the door so that the member 64 may be swung through this panel in a clockwise direction from the position in which it is shown in Figure 3 of the drawings, an abutment 69 on the latch casing 22 serving to engage the member 50 to limit the rearward movement of this member and consequently the extent to which the member 64 may be displaced through the opening 67.

The pillar 12 is provided with a recess 70 therein which is adapted to receive cooperating threaded members 71 and 72, the latter being provided with headed portions whereby they may be threaded together to clamp them in position in the recess 70 as shown in Figure 3. The member 72 is preferably provided with a non-circular peripheral portion engaging a correspondingly shaped aperture 73 in the pillar facing to prevent rotation thereof. The members 71 and 72 are further provided with an aperture 74 therethrough, preferably non-circular as shown in Figure 4, in which is received a correspondingly shaped bolt 75, the latter being provided with a longitudinally extending slot 77 in which is disposed a pin 78 secured in the member 72, whereby the bolt 75 may partake of limited longitudinal sliding movement within the members 71 and 72 but is retained against rotation.

The bolt 75 extends between and in the closed position of both doors normally engages at its opposite ends with the member 64 and a similar member 80, the latter being pivoted as at 81 to the latch casing 22 for the rear door panel and being pivotally connected by means of a link 84 with a member 85, the latter corresponding to the member 50 hereinbefore described and being supported on the latch casing by guides 86 for longitudinal sliding movement. The member 85 is provided with a recess 87 receiving a cam 88, the forward cam surface of the latter engaging a lug 89 struck up from the member 85. Forward rocking movement of the member 80 through the aperture 91 formed in the edge panel 92 of the rear door is limited by means of an abutment 93 on the latch casing 22 arranged to engage the member 85 to limit the forward movement of the latter.

The cam 88 is pivotally supported at 95 on the latch casing 22 and is provided at its lower end with a roller 96 engaging an abutment 97 corresponding to the abutment 59 and similarly secured to the associated locking plate 21.

The operation of the construction thus far described will be apparent. When the handle 15 associated with the front door 10 is moved in a counterclockwise direction, the link 20 and associated locking plate 21 are moved rearwardly to lock the door as hereinbefore explained, and to rock the member 64 through the aperture 67, thus thrusting the bolt 75 rearwardly. This movement of the bolt 75 is communicated to the member 80 and thence through the link 84 to the member 85 which in turn rocks the cam 88 in a clockwise direction so that the locking plate 21 is moved forwardly. The dogging abutment 35

is thus moved beneath the projection 43 on the roll back 42 to lock the rear door 11. The front door may now be locked and unlocked at will without disturbing the locking mechanism associated with the rear door, although operation of the handle 15 on the rear door to unlock the latter will at the same time unlock the front door through the forward displacement of the bolt 75.

In lieu of the construction illustrated in Figures 1 to 3 inclusive employing a bolt 75, either of the arrangements shown in Figures 5 and 6 may be used. Thus in Figure 5 a bolt 100 is provided for direct engagement with the cam 54, this bolt being carried by the latch casing 22 of the forward door for reciprocal movement by means of a bracket 101. The bolt 100 engages a member 104 which is pivoted as at 105 to a bracket 106 carried by the pillar 12. A similar member 108 pivoted as at 109 to a bracket 110 secured to the pillar is connected with the member 104 by means of a link 112 pivoted to both, the construction constituting in effect a double hinge. The member 108 engages a bolt 115 which is slidably supported in a bracket 116 carried by the latch casing 22 associated with the rear door of the vehicle, the bolt 115 being connected by means of a link 118 to the upper end of the cam 88. The construction may otherwise correspond to that shown in the first three figures of the drawings and the mode of operation is the same, it being obvious that the cam 88 will be oscillated in response to displacement of the cam 54 to effect locking of the rear door when the forward door is locked.

In the arrangement shown in Figure 6 of the drawings the construction corresponds to that illustrated in Figure 5 with the exception that the bolts 100 and 115 engage resilient elements 120 and 121 respectively which are secured as at 122 to the pillar 12 at opposite sides thereof. A thrust element comprising a bolt 124 threaded in a recess 125 in a nut element 126 is slidably supported in a sleeve 128 fitted snugly within a corresponding recess extending through the pillar 12, the bolt 124 and nut 126 being locked by means of a lock nut 129, so that the length of this thrust member may be readily adjusted. At its ends the thrust member abuts the resilient elements 120 and 121 so as to transmit motion from the locking mechanism for the front door to that of the rear door. The resilient elements 120 and 121 will normally retain the thrust element in an intermediate position within the pillar so that the doors may be closed without risk of damaging the parts of the interconnecting mechanism. With this construction any play which may be present at any point in the mechanism may be reduced to a minimum by proper adjustment of the length of the thrust element.

The construction shown in Figures 7, 8, and 9 of the drawings is provided for the purpose of facilitating the unlocking of the rear door of the vehicle, which in the conventional construction requires manipulation of the handle 15 associated with the rear door. For convenience in illustrating and describing this construction, locking mechanisms for the doors identical with those shown in Figures 1 to 3 are employed, and similar reference characters are employed to designate similar parts. Means are provided, however, to normally displace the bolt 75 carried by the pillar 12 to the forward position and to normally urge the various elements of the locking mechanism for the rear door to a position 75 in which that door is unlocked. This means may

comprise a spring seat 135 carried by the latch casing 22 for the rear door and serving as an abutment and guide for a coil spring 136 which in turn engages a lug 138 struck up from the member 85, the latter being supported for sliding movement on the latch casing 22 and having an articulated connection through the link 84 with the pivoted member 80 as in the form of the invention shown in Figures 1 to 3 inclusive. The cam 88 may be provided at its lower end with a closed or pivotal connection to the locking plate 21 or, as shown in Figure 7 of the drawings, a coil spring 140 may be connected to a lug 141 formed on or carried by the latch bolt 25 and a member 143 secured to or carried on the locking plate 21 and having a lug 144 engaged by the roller 96 of the cam 88, it being only necessary to ensure that the locking plate 21 will follow the movements of the cam 88 in either direction.

In order that the rear door will remain locked when the mechanism is once displaced to locking position and until it is desired to unlock the door, means are provided for retaining the bolt 75 against forward displacement in the pillar 12 under the influence of the coil spring 136. This means is shown more particularly in Figures 8 and 9 of the drawings and may include a housing 146 having an aperture 147 extending therethrough in which the bolt 75 is disposed, a similar aperture 148 being provided in an element 149 having a threaded connection as at 150 with the housing 146 and serving to clamp the latter in position in the opening 152 provided in the pillar 12. The bolt 75 is provided with a recess 154, and a pin 155 suitably secured at its ends within the housing 146 is disposed within this recess to limit reciprocal movement of the bolt 75 and to prevent rotation thereof.

The bolt 75 is also provided with recesses 158 and 159 disposed in spaced longitudinal relation, these recesses being selectively engageable by the rounded end 160 of a pin 161, the latter having a headed portion 162 slidably in an aperture 163 within the housing 146 and transversely of the pin 75. A member 169 is formed to receive 45 therein a coiled spring 170, the latter acting under compression between the member 169 and the pin 161. The member 169 is further provided with a rounded end 172 which normally engages the cylindrical surface of plunger 174 having an operating button 175 at the outer end thereof. The plunger 174 is slidably supported in the housing 146, sliding movement thereof being limited by means of an abutment 177 engaging a slot 178 in the plunger, the abutment 177 having a portion 179 threaded within a recess 180 in the housing 146. A coiled spring 182 acts under compression between the rear end of the plunger 174 and a spring seat 183 having threaded connection with the housing 146 to normally maintain the plunger in the position shown in Figure 9. The plunger 174 is further provided with a recess 185 having preferably the configuration shown which is arranged to accommodate the headed portion 172 of the member 169 when the plunger is displaced rearwardly by pressure applied by the finger to the button 175.

The stress initially applied to the coiled spring 170 is sufficient when the parts occupy the position in which they are shown in Figure 9 of the drawings to retain the bolt 75 against displacement forwardly in response to the action of the spring 136, the pin 161 being seated in the aperture 159. When, however, the plunger 174 is 75

displaced rearwardly to permit the rounded end 172 of the member 169 to seat within the recess 185 in the plunger, the degree of compression of the spring 170 is relieved to an extent sufficient 5 to permit the spring 136 to displace the member 85 and the bolt 75 forwardly so that the pin 161 will drop within the recess 158, the spring 140 then displacing the locking plate 21 for the rear door to the unlocked position in the manner 10 hereinbefore explained.

It is obvious that with this construction the rear door can be unlocked at any time by manipulation of the usual handle 15 associated therewith, the resistance offered by the spring 170 and 15 pin 161 to a forward movement of the bolt 75 being relatively small. When, however, it is desired to unlock the rear door without reaching into the rear compartment of the vehicle, the 20 application of slight pressure to the button 175 will suffice.

It is apparent that considerable rearrangement of the structure described is permissible without affecting the underlying principles. For 25 instance, button 175 may be made accessible from the inner face rather than the forward edge of the pillar 12 by disposing the plunger at right angles to the position in which it is shown in the drawings. Numerous other changes will readily occur to those skilled in the art to which the 30 invention relates, such changes being deemed within the scope of the present invention.

Having thus described the invention, what is claimed as new and desired to be secured by Letters Patent is:

- 35 1. In a vehicle having a front door, a rear door, and a pillar intermediate said doors, the combination with locking mechanism carried by said rear door and cooperating with said pillar to retain said rear door in closed position, of manually operable means carried by said pillar and associated with said locking mechanism for releasing the latter, said means being covered by said front door in the closed position of the latter.
- 40 2. In a vehicle having doors at the same side thereof and a pillar intermediate said doors, the combination with locking mechanism carried by one of said doors and cooperating with said pillar to retain such door in closed position, of manually operable means carried by said pillar and associated with said locking mechanism for releasing the latter, and manually operable means carried by the other of said doors and connected with said locking mechanism for actuating the latter to lock said first named door.
- 45 3. In a vehicle having doors at the same side thereof and a pillar intermediate said doors, the combination with locking mechanism carried by each of said doors and cooperating with said pillar to retain said doors in closed position, of manually operable means carried by each door for actuating the associated locking mechanism to lock and release the door, and means affording a mechanical connection between said locking mechanisms, whereby the manually operable means carried by one only of said doors actuates both locking mechanisms to concurrently lock both doors, and whereby the manually operable means carried by the other only 50 of said doors actuates both locking mechanisms to concurrently release both doors.
- 55 4. In a vehicle having doors at the same side thereof and a pillar intermediate said doors, the combination with locking mechanism carried by each of said doors and cooperating with

said pillar to retain said doors in closed position, of manually operable means carried by each door for actuating the associated locking mechanism to lock and release the door, and linkage affording a mechanical connection between said locking mechanisms, said linkage being movable in one direction by the locking mechanism of one only of said doors to actuate the locking mechanism of the other door, and movable in the opposite direction to release the locking mechanism of said first named door only by the releasing movement of the locking mechanism of said second named door. 5

5. In a vehicle having doors at the same side thereof and a pillar intermediate said doors, in combination, locking mechanism carried by each of said doors and cooperating with said pillar to retain said doors in closed position, each of said locking mechanisms comprising a bolt, a roll back, and a dog for said roll back, linkage 20 affording a mechanical connection between said dogs whereby upon movement of one of them into position to dog its roll back said linkage will be moved in a direction to cause the other dog to be moved into position to dog its roll 25 back, said linkage being movable in the opposite direction to release said first named dog only by movement of said second named dog to release its roll back.

6. In a vehicle having doors at the same side 30 thereof and a pillar intermediate said doors, in combination, locking mechanism carried by each of said doors and cooperating with said pillar to retain said doors in closed position, each of said locking mechanisms comprising a bolt, a roll 35 back, and a dog for said roll back, an exterior handle for each of said roll backs and an interior handle for each of said dogs on the respective doors, linkage extending between said doors and having a lost motion abutment connection with each of said dogs whereby movement of the dog of one of said doors into position to dog its roll back will move the other dog into position to dog its roll back and releasing movement of said second named dog 40 will move said first named dog also to releasing position, resilient means continuously urging said linkage to releasing position, resiliently urged detent means for retaining said linkage in dog holding position against the action of said 45 urging means but not against positive releasing action of said dog actuating handles, and manual means for releasing said detent means to enable the resilient means to move the dog to releasing 50 position. 55

7. In a vehicle having a master door and a secondary door at the same side thereof and a pillar intermediate said doors, in combination, locking mechanism carried by each of said doors and cooperating with said pillar to retain said doors in closed position, each of said locking mechanisms comprising a bolt, a roll back, and a dog for said roll back, an exterior handle for each of said roll backs and an interior handle for each of said dogs on the respective doors, linkage extending between said dogs and through said pillar and having a lost motion abutment connection with each of said dogs whereby movement of the dog of the said master door to position to dog its roll back will move the dog of said secondary door into position to dog its roll back, and releasing movement of said second named dog will move said first named dog also to releasing position, resilient means continuous- 70 75

ly urging said second named dog to releasing position, resilient means continuously urging said linkage to releasing position, resiliently urged detent means in said pillar for retaining said linkage in dog holding position against the action of said urging means but not against positive releasing action of said handles, manual

means in said pillar for releasing said detent means to enable the resilient means to move the dog to releasing position, said manual means being concealed and covered by a portion of said master door when the latter is closed.
